UNITED STATES PATENT OFFICE.

THOMAS L. SCHOFIELD, OF PHILADELPHIA, PENNSYLVANIA, ASSIGNOR TO THE S. S. WHITE DENTAL MANUFACTURING COMPANY, OF PHILADELPHIA, PENNSYLVANIA, A CORPORATION OF PENNSYLVANIA.

DESIGN FOR A BOTTLE.

48,265.

Specification for Design.

Patented Dec. 7, 1915.

Application filed October 20, 1915. Serial No. 57,000. Term of patent 14 years.

To all whom it may concern:

Be it known that I, THOMAS L. SCHOFIELD, a citizen of the United States, and a resident of Philadelphia, county of Philadelphia, State of Pennsylvania, have invented a certain new, original, and ornamental Design for Bottles, whereof the following is a specification, reference being had to the accompanying drawings, forming part thereof.

In the accompanying drawings, Figure 1 is a plan view of the bottle embodying my new design; Fig. 2 is a front elevational view of the bottle shown in Fig. 1; and Fig.

3 is a side elevational view as seen from the left side of Figs. 1 and 2.

I claim:

The ornamental design for bottle substantially as shown.

In witness whereof, I have hereunto set my hand this 19th day of October, A. D., 1915.

THOMAS L. SCHOFIELD.

Witnesses:

WILLIAM J. RUSSELL,
CLIFTON C. HALLOWELL.
